(57) **CLAIM**

The ornamental design for a cookware lid handle, as shown and described.

DESCRIPTION

FIG. 1 is a top, front, right-side perspective view of a cookware lid handle;

FIG. 2 is a front elevation view thereof, the rear elevation view being a mirror image;

FIG. 3 is a left side elevation view thereof, the right side elevation view being a minor image;

FIG. 4 is a top plan view thereof; and,

FIG. 5 is a vertical cross-section view thereof, taken along line 5-5 of FIG. 3.

In the drawings, the broken lines are for the purpose of illustrating environment only, and form no part of the claimed design.

1 Claim, 3 Drawing Sheets
